UNITED STATES PATENT OFFICE.

ALLISON DALRYMPLE SMITH, OF EDINBURGH, SCOTLAND, ASSIGNOR OF TWO-THIRDS TO CHARLES STEWART ROLLS, OF SOUTH LODGE, KNIGHTSBRIDGE, ENGLAND, AND NORMAN DORAN MACDONALD, OF EDINBURGH, SCOTLAND.

STEAM-BOILER FOR MOTOR-VEHICLES.

SPECIFICATION forming part of Letters Patent No. 718,954, dated January 20, 1903.

Application filed July 1, 1901. Serial No. 66,734. (No model.)

To all whom it may concern:

Be it known that I, ALLISON DALRYMPLE SMITH, mechanical engineer, a subject of the King of Great Britain, residing at 14 Hartington Gardens, Edinburgh, Scotland, have invented certain new and useful Improvements in and Relating to Steam-Boilers for Motor-Vehicles and other Like Uses, (for which an application was made in Great Britain, dated December 8, 1900, No. 22,368,) of which the following is a specification.

This invention relates to an improved water-tube boiler especially designed for use in a motor-vehicle.

In carrying out my invention I, in the case of a vertical boiler, form the upper and lower multiples as rings of somewhat oblong cross-section, the tubes running from the inner ends of the respective multiples, their ends being fixed into the multiples in usual manner. These multiples of annular form I produce from steel or other suitable metal, preferably rolled in the form of weldless rings, and then partially or wholly turning the internal chamber from the solid to the desired design, preferably thickening the metal toward the outer wall, forming the open end, so as to adapt it for the tap-holes to be formed therein for studs by which to securely hold the cover-plate ring to close such open side of each multiple. This enables the two sides of each ring to be kept close together, whereby great strength and economy are attained, together with a minimum number of joints.

Figure 1 shows by an external elevation the arrangement of the parts for a vertical boiler. Fig. 2 is a vertical section of the boiler arranged according to my invention, taken on the line A A of Fig. 5. Fig. 3 is a horizontal section taken on the line B B of Fig. 2. Fig. 4 is a horizontal section taken on the line C C of Fig. 2. Fig. 5 is a plan view taken with the gage and other usual adjuncts indicated in Figs. 1 and 2 omitted. Figs. 6 and 7 show details of construction separately to a larger scale.

The figures show a vertical boiler consisting of the upper multiple *a* and lower multiple *b*, each of oblong cross-section, as more

clearly shown by the detail sectional views, 50 Figs. 6 and 7.

c c are tubes connecting the upper multiple *a* with the lower multiple *b*, and these tubes are fixed in usual manner to those parts.

d d are studs tapped into the thickened portion of the walls of the upper multiple at *a'*, which studs serve to retain the cover-plate ring *e*. *ff* are corresponding studs tapped into the thickened portions *b'* of the lower multiple *b* to retain the cover-plate ring *g*. 60

h represents the fire-bars. These fire-bars may, as shown, be of circular form as a whole, divided into, say, three sections for convenience of removal, or otherwise. The bars on which the fuel rests are shown as straight 65 and in cross-section at top angular, as at *h'*, tapering at *h*² downward from the base of the upper angles for a considerable depth, and finishing in a blunt curve *h*³. Each bar, as shown, may be deeper from edge to center, 70 and each bar of greater length also has a greater depth toward its center, so that the whole under side of the fire-bars in contour approximates to a section of a circle in every direction. 75

The vertical tubes may be of solid drawn steel. The annular wall *i i* of the fire-space *j* is of steel or other suitable metal lined with asbestos, as at *k*, or like non-conducting material. 80

Partially closing the opening *l* at the upper end—that is to say, within the circumference of the upper multiple *a*—is secured a steam and water drum or vessel *m*, having diminished ends forming necks *m' m'*, each of which is turned so that it fits accurately to the upper multiple *a*, and the opening *m*² of each neck is brought exactly opposite a hole *a*² in the inner side of the said multiple *a* and then secured, preferably, as shown, by a short 85 length of boiler-tubing or a species of ferrule *n n*, which is passed from within the annular chamber of the multiple *a* into the meeting apertures *a*² *m*² in the multiple *a* and the neck, respectively, and these tubes *n n* are expanded 90 therein by a suitable tool and a good joint secured. The segmental ends *m*² of this steam and water chamber *m* rest butt against the 95

upper multiple *a*, which ring takes off the pressure, and any tendency to burst out the ends of the drum is thus counteracted. A convenient safety-valve passage, as at *o*, can 5 be carried up from the steam-drum to without the boiler-casing. In the upper part of the steam-drum I may also form a dome or extension upward, *p*, and from within this I take steam by a tube *q*, which extends up- 10 ward toward the top thereof and, passing away through one of the necks of the drum *m*, is secured in the wall of the multiple *a* and then is connected to the main steam-valve and is continued to the engine. The lower 15 part of the drum *m* may be provided with a suitable fusible plug, as at *r*, and connec- tions.

In the upper part of the casing is provided a convenient chimney *s* and a door *t*, through 20 which to effect the stoking and fuel-supply.

Among the advantages attendant on this construction of upper and lower multiples for connection to the tubes is the facility afforded for quickly cleaning out any fouled tubes by 25 simply removing the cover-plate or base-ring by removing the nuts from their studs, when all the tubes will be accessible from below. If a tube burst or otherwise requires to be removed, it becomes only necessary to re- 30 move the top of the casing, the upper annular cover-plate of the upper multiple, and the corresponding plate of the lower multiple to knock out the damaged tube and replace it by a fresh one without having to disturb the 35 adjustments of the other parts. The number of parts in the construction is also by my invention greatly reduced.

The usual boiler-mountings are applied as needed.

40 Having now particularly described and ascertained the nature of my said invention and in what manner the same is to be performed, I declare that what I claim is—

1. A multiple for steam-boilers comprising 45 an annular hollow body having a continuous opening in one end, the inside walls of said hollow body being inclined toward each other as they approach the said open end to provide side walls of gradually-increasing thickness 50 and a closure-plate for said opening.

2. A multiple for steam-boilers comprising an annular hollow body having a continuous opening in one end, the inside walls of said body being inclined toward each other as they 55 approach the said open end to provide side walls of gradually-increasing thickness, the outer and inner edges of said side walls adjacent to the open end being enlarged or thickened, and a covering-ring or annulus for said 60 open end.

3. A multiple for steam-boilers comprising in its construction an annular hollow body having a continuous opening in one end, the inner faces of the side walls of said hollow body being inclined toward each other as they 65 approach the said open end to provide side walls of gradually-increasing thickness.

4. In a steam-boiler for motor-vehicles and the like, an upper and a lower annular multiple suitably communicating with each other, 70 a drum having two sides shaped to conform to the inner peripheral wall of the upper multiple and secured to the latter at these points, said drum having communication with the multiple to which it is attached, a dome rising from the drum, and a steam-pipe extending from within the dome through the drum and upper multiple for supplying steam to an engine.

5. In a steam-boiler, the combination with 80 an upper annular multiple, of a lower multiple, pipes for establishing communication between said multiples, a drum arranged within the opening formed by the annular multiple and having two sides shaped to conform to the inner peripheral wall of said multiple and embracing said wall to form a close fit between these parts, a pair of tubes extending through the connecting-walls of the drum and multiple respectively for establishing 85 communication between these elements, and a steam-pipe leading from the drum.

6. In a steam-boiler for motor-vehicles and the like, an upper and lower multiple, pipes for establishing communication between the 90 said multiples, fire-bars arranged within the lower multiple, a drum arranged within the upper multiple, a pair of tubes extending in the drum and in the upper multiple for connecting the latter to the former and establishing communication between them, a dome connected to the top of said drum and communicating therewith, and means extending in the dome and through the drum and upper multiple for supplying the engine with steam. 95

7. In a steam-boiler, an upper and a lower multiple having intercommunicating pipes, a drum secured to the upper multiple and having communication therewith, a dome rising from the drum, and a steam-pipe leading 100 from the dome and extending through the drum and upper multiple, substantially as described.

In testimony whereof I have hereunto set my hand in presence of two subscribing witnesses. 115

ALLISON DALRYMPLE SMITH.
